CODE TRANSMITTING APPARATUS IN
TRACK CIRCUIT SIGNALING SYSTEMSMarcian A. Scheg, Rochester, N. Y., assignor to
General Railway Signal Company, Rochester,
N. Y.

Application August 31, 1944, Serial No. 552,108

4 Claims. (Cl. 246—38)

1

The present invention relates to block signalling systems for railroads using coded track circuits, and more particularly pertains to the improvement of the code transmitting apparatus employed in such signalling systems.

Each block of a signalling system employing coded track circuits usually comprises a single track circuit extending throughout the length of such block with suitable code transmitting apparatus at one end of the track circuit and suitable code responsive means at the other end. The code transmitting apparatus usually applies code pulses at different distinctive rates to provide the different codes in accordance with traffic conditions, although various different types of codes may be employed. Since coded track circuits are thus usually relatively long, as above mentioned, a substantial current flow occurs during the application of each code pulse especially when the ballast along the trackway drops in resistance to its lowest value under adverse conditions. Also, when a train enters a block and shunts the track rails at the code receiving end of the track circuit, the code transmitting apparatus continues operation at the leaving end of the block and in so doing must supply a relatively large current during the application of each code pulse.

In view of this fact that the code transmitting apparatus of a coded track circuit must under certain conditions supply code pulses of relatively high current values at very low potentials, it is apparent that a problem is presented in providing contacts on the code transmitting apparatus which will adequately handle such relatively high currents and yet be of sufficiently low contact resistance as to not materially affect the applied potential.

The present invention proposes to obviate these difficulties by applying direct current code pulses to the track rails of a track circuit through a rectifier supplied from an alternating current source with suitable means for controlling the application of the alternating current potential to the rectifier in a manner so as to minimize the value of current to be broken by the coding contacts. Since the energy is to be provided from an alternating current source, it is proposed that the coding contacts control the energy at potentials higher than that supplied to the track rails but with correspondingly reduced current values, and in this way make it possible to employ relatively high resistance non-arcing contact material, such as tungsten, or the like.

In many coded track circuits it is not only de-

2

sirable to transmit driven code pulses in one direction over the track rails, but it is also desirable to transmit so-called inverse code pulses between the successive driven code pulses in an opposite direction over the track circuit. In order to accomplish this, it will be evident that the direct current carrying circuits connecting to the track rails must be commutated in order to include and exclude the code transmitting and code receiving apparatus at each end of the track circuit. Thus, another object of the present invention is to so control the application of energy through the code transmitting apparatus as to minimize the current to be carried by the commutating contacts.

Generally speaking, and without attempting to define the exact nature and scope of the present invention, it is proposed in one form of the invention to provide the energy for a coded track circuit by connecting the alternating current source through a full-wave rectifier with a resonated impedance included in series with the alternating current source and the rectifier, which resonated impedance may be shunted and unshunted by suitable code transmitting contacts so as to control the supply of current to the track rails. In order that such coding contacts may be of the high resistance arc resistance type, it is proposed that the resonated impedance be of the auto-reactor type so as to raise the voltage to be governed by the coding contact considerably above that supplied to the rectifier.

It is also proposed that the commutating contact, which is included in the direct current side of the rectifier so as to connect the rectifier and a code receiving relay alternately across the track rails, be suitably adjusted with respect to the coding contacts, so that the control of the current by the resonated auto-reactor is effected subsequent to the closure of the commutating contacts and prior to their opening.

In another form of the present invention, it is proposed that the secondary windings of two like transformers be connected in series across the terminals of a rectifier but with their potentials in opposition to each other. Under such a condition, there is no current flow through the rectifier to the track rails. The coding contacts are arranged to control one of the transformers so as to deenergize it and remove its opposing potential, and thus allow a potential to be applied from the directly connected transformer to the rectifier to cause a current flow in the track rails. In this way, the coding con-

tacts by controlling such opposing transformer merely have to carry current of a sufficient value to supply the transformer losses; while the load current is directly supplied by the other directly connected transformer. It is also proposed that this form of the invention be adapted to the commutation of the low voltage direct current portion of the connections to the track circuits so as to provide for the transmission and reception of inverse codes as well as the driven codes.

Other objects, purposes and characteristic features of the present invention will be in part obvious from the accompanying drawings, and in part pointed out as the description progresses.

In describing the invention in detail, reference will be made to the accompanying drawings, in which those parts having similar features and functions are designated by like letter reference characters which are generally made distinctive by reason of distinctive preceding numerals representative of their location or association with other devices having reference characters with like numerals, and in which:

Fig. 1 illustrates in a diagrammatic manner one form of a coded track circuit system embodying the present invention and employing a resonated reactor for controlling the coded track circuit energy;

Fig. 1A illustrates a modified form of inverse code receiving track relay for use in Fig. 1;

Fig. 1B illustrates a modified form of resonated reactor for use in Fig. 1; and

Fig. 2 illustrates another form of coded track circuit system embodying the present invention in which opposing alternating current potentials are provided to intermittently limit the current flow in the track circuit to produce the code pulses.

For the purpose of simplifying the illustration and facilitating the explanation, the various parts and circuits constituting the embodiment of the invention have been shown diagrammatically and certain conventional illustrations have been employed, the drawings having been made more with the purpose of making it easy to understand the principles and mode of operation than with the idea of illustrating the specific construction and arrangement of parts that would be employed in practice. Thus, the various relays and their contacts are illustrated in a conventional manner, and symbols are used to indicate the connection of terminals to batteries or other suitable sources of electric current instead of showing all of the wire connections to these terminals.

The symbols (+) and (-) are employed to indicate the positive and negative terminals respectively of suitable batteries or other sources of direct current; and the circuits with which these symbols are employed are assumed to always have current flowing in the same direction, although it is to be understood that in some cases alternating current might be substituted for the direct current, and in such cases the (+) and (-) are to be considered as indicating the relative instantaneous polarities of the alternating current. In some of the circuits, alternating current is employed, and the opposite terminals of a suitable source or sources for such alternating current circuits have been indicated by the symbols (BX) and (CX).

With reference to Fig. 1 of the accompanying drawings, a stretch of track has been divided into track sections by suitable insulated joints of which the track section 2T has been shown completely and the track sections 1T and 3T in part

only. Color light type signals 2 and 3 are shown at the entrance ends of the track sections 2T and 3T respectively, assuming a normal direction of traffic from left to right. These signals can of course be of any suitable type desired.

At the exit end of each track section (such as section 2T), a suitable code transmitting apparatus is located to transmit driven codes of different distinctive rates in accordance with traffic conditions in advance as governed by the code receiving means for the entrance end of the next adjoining track section. This apparatus also has associated therewith suitable inverse or off code receiving means which detects the presence of an approaching train and can be used for approach lighting signals, highway crossing protection, approach locking and the like.

At the entrance end of each track section (such as section 2T), a suitable code receiving apparatus is located for receiving the different driven codes and decoding them so as to properly control the associated signal. Also, associated with this code receiving apparatus is suitable inverse or off code transmitting apparatus, for transmitting inverse code pulses during the off periods between successive driven code pulses.

As typical of all such track sections above briefly described, reference may be made to the track section 2T of Fig. 1, in which a code transmitter relay 3CP of the neutral type is energized and deenergized in accordance with different code rates as selected by the home signal relay 3H associated with the signal 3. More specifically, when front contact 5 of relay 3H is closed, a coding contact 180C energizes the relay 3CP at the clear code rate of 180 times per minute, but if the back contact 5 of relay 3H is closed the relay 3CP is energized at the caution code rate of 75 times per minute. It is to be understood that the relay 3H is deenergized whenever a train is in the track section 3T, but is picked up whenever a caution or clear code rate is being received at the signal 3 location. Also, the usual clear and caution code rates of 75 and 180 pulses per minute have been selected for the coders 75C and 180C for the purposes of this disclosure, but it should be understood that other suitable code rates might be selected.

Each of the code transmitter relays, such as relay 3CP, is provided with at least two contacts, one of which is conveniently termed an "advanced" contact while the other of which is termed a "retarded" contact. Each advanced contact *a* is so connected to its operating armature as to close its front contacts prior to the closure of the front contact of its associated retarded contact *b*; while the opening of the advanced front contact *a* is effected subsequent to the opening of the retarded contact *b*. Although this relative advance and retardation of contacts *a* and *b* may be of any suitable amount for accomplishing the purposes of the present invention, it has been found in one typical embodiment that the advanced contact *a* may be closed approximately ten thousandths of an inch earlier than the retarded contact *b*, which difference in inches of course refers to the air gap adjustment. This relative closing of the contacts has been indicated on the drawing by a suitable legend.

Also, associated with the leaving end of track section 2T is an inverse code receiving track relay 3ATR. This relay is of the magnetic stick type as indicated in the drawings, and thus its contacts are operated to opposite positions upon the energization of such relay in opposite direc-

tions, and such contacts remain in their last actuated positions until the relay is energized in the opposite direction. This relay is shown as having three windings for purposes which will be described hereinafter.

The opposite terminals (BX) and (CX) of a suitable alternating source supplies energy to the primary winding of a transformer 3TF, and the secondary of this transformer supplies energy at a suitable voltage to the input terminals of the rectifier 3R. The current flow in this circuit must pass through the winding 6 of an auto-reactor unit 3RT which has a second winding 7. Connected across the outer terminals of the auto-reactor 3RT is a suitable condenser 9 which is preferably of such a value as to resonate the inductive reactance of the auto-reactor 3RT, although it should be understood that the inventions may be practiced although exact resonance is not accomplished. The resonant condition is of course for the same frequency of alternating current as supplied to the transformer 3TF. The outer terminals of the auto-reactor 3RT are shunted and unshunted by contact 8 of the code transmitting relay 3CP, as will presently be described.

The primary winding of the transformer 3TF may be connected to the usual commercial supply of 60 cycle alternating current at 110 volts for example, while its secondary winding may be of such a ratio as to produce 6 volts, for example. This voltage supplied to the input of the rectifier 3R through the winding 6 of the auto-reactor 3RT will supply a relatively small current through front contact 10 of the transmitter relay 3CP to the track circuit when this advanced contact 10 initially closes and connects the output of the rectifier 3R through the resistor 11 to the lower track rail and the other terminal of the rectifier 3R through the lowest winding of the inverse track relay 3ATR to the upper rail of the track section 2T. This is because the resonant impedance of the auto-reactor 3RT is very high and limits the current to a low value such as 75 milliamperes for example. But as soon as the retarded contact 8 closes its front points, the outer terminals of the auto-reactor 3RT are shunted so that the impedance of the auto-reactor 3R is reduced to substantially the resistance drop through its winding 6, and the current thus supplied to the track rails of the track section 2T is in accordance with that required under the particular adjustment of the limiting resistor 11 and the conditions of the track section including the track relay 2TR. This is because the closure of front contact 8 shunts the condenser 9 and destroys the resonant condition, and also shunts the effective secondary of the auto-reactor 3RT which reduces its inductive reactance to substantially zero. The winding 6 of the auto-reactor 3RT is of relatively large wire so that its resistance is low compared to winding 7. Thus, the effect of the auto-reactor 3RT on the input to the rectifier 3R is relatively slight under its shunted condition. The current which flows in the lower winding of the inverse code receiving track relay 3ATR passes through the relay in such a direction as to cause its contacts to be moved to their lower or dropped away positions, as indicated by the arrow within the lower winding.

Since the winding 7 of the auto-reactor 3RT has a greater number of turns than the winding 6, the potential across the outer terminals of the auto-reactor 3RT, before the outer terminals are

shunted, is considerably higher than the potential given by the secondary winding of the transformer 3TF, and this higher potential may be made of any desired value by properly selecting the ratio of the two reactor windings. However, this potential should be sufficiently high that the retarded contact 8 may be constructed of suitable relatively high resistance arc resisting material, such as tungsten, for example, so that it may readily produce a shunt across the outer terminals of the reactor and yet provide a sturdy and reliable contact for breaking any current flow upon the opening of the contact 8.

It will be mentioned at this point that the advanced contact 10 is preferably constructed of a suitable low resistance material such as silver so that the relatively low potentials applied to the track circuit will not be materially changed by the inclusion of the contact, and so that such potentials will be reliably maintained at the same values for successive impulse periods.

At the end of each pulse period the relay 3CP is dropped away thus opening the retarded contact 8 prior to the opening of advanced contact 10. The opening of contact 8 of course unshunts the auto-reactor 3RT and its inductive reactance is inserted into the input circuit of the rectifier 3R prior to the opening of contact 10. This reduces the current in the track circuit energy applying circuit to a very low value, so that the opening of contact 10 breaks a relatively small current such as 75 milliamperes as compared to a track circuit pulse current which may under some conditions be as high as 10 to 15 amperes. Any arc which is made at the contact 8 has a very small current value in view of the reactor winding ratio and the relatively high resistance of winding 7. Also, any arc that might be produced at this contact is substantially absorbed by the condenser 9. In other words, the condenser 9 serves two purposes, namely, that of resonating the auto-reactor 3RT, and also suppressing any arc across the contact 8.

While the back contact 10 of the transmitter relay 3CP is closed, the intermediate winding of the inverse code receiving track relay 3ATR is connected across the track rails of section 2T for receiving an inverse code pulse, if there is one, and actuating its contacts to an upper position as indicated by the arrow included within its winding. The operation of the driven code receiving and inverse code transmitting apparatus at the other end of the track section 2T will be described hereinafter, but for the present it is sufficient to understand that an inverse code pulse may be received at the leaving end of the track section 2T and this will flow in such a direction that the contacts of this relay 3ATR are picked up. This differential connection of the windings of relay 3ATR will be readily apparent from the drawing of the circuits. The current flow in the inverse track relay 3ATR during an inverse code pulse can be suitably adjusted by the limiting resistor 14. Upon the cessation of the inverse code pulse, and when the next driven code pulse is applied by the transmitter relay 3CP in a picked up position, the current flow through the lower winding of the relay 3ATR is in such a direction to cause its contacts to be actuated to their lower positions.

It will thus be seen that this relay 3ATR is alternately operated to its opposite positions, being caused to have its contacts moved to their upper positions by inverse code pulses and having its contacts moved to lower positions in re-

sponse to driven code pulses. Upon the cessation of inverse code pulses, the contacts of the relay are of course maintained in their lower positions to which they are actuated by the first driven code pulse following the last received inverse code pulse.

Associated with this inverse code receiving track relay 3ATR is a suitable decoding relay 3AH which has an associated decoding transformer 12 of the usual mid-tapped type controlled by contacts on the relay 3ATR in the usual way. Thus, whenever the relay 3ATR receives inverse code pulses, the relay 3AH is picked up, but when the relay 3ATR ceases to receive inverse code pulses this relay 3AH is dropped away to close its back contact 13 and thus approach light the signal 3.

It will be appreciated that each inverse code pulse will be of relatively short duration, and since the relay 3ATR is restored to its dropped away position due to the application of the driven code pulse, it will be readily apparent that the relay 3ATR would ordinarily be in a picked up position for a relatively short time compared to the duration of an "off" period or an "on" period of the driven code. But in order that the contacts of the relay 3ATR may be in their picked up positions for such a time as to make the picked up condition of substantially the same duration as the dropped away condition during the reception of inverse code pulses, it is proposed to make the relay 3ATR slow to be restored to its lower position, although quick to be operated to its upper position in response to a relatively short inverse code pulse. To accomplish this result with the magnetic stick type relay 3ATR, its upper winding is provided with a shunt circuit through a front contact 15. The slow action produced by the shunting of this upper winding, is effective only upon the energization of the relay by energy during a driven code pulse flowing through a local circuit of the relay to delay its operation to its lower position. The amount of retardation may be regulated by the number of turns and resistance of such turns as shorted through this contact 15, but it is preferable that this be arranged so as to cause the relay 3ATR to be picked up for substantially the same time that it is dropped away. This gives a better decoding operation of the relay 3AH.

At the entering end of the track section 2T, and associated with the signal 2, is a track relay 2TR, which is preferably of the polarized type, that is, its contacts are biased to one position by gravity or suitable resilient means, and are operated to picked up or actuated positions in response to only a particular polarity. This track relay 2TR is connected through a limiting resistor 20 and the advanced back contact 21 of the repeater track relay 2TPA to the track rails of the track section 2T. Each driven code pulse causes the contacts of the relay 2TR to be picked up, while the deenergization of the track section 2T between two successive driven code pulses results in the releasing of the contacts of this relay 2TR. The successive operation of the track relay 2TR in response to driven code pulses causes suitable decoding apparatus to be controlled through contact 22 so as to pick up the distant relay 2D in response to the clear code of the 180 code rate as well as the home relay 2H, but to pick up only the relay 2H in response to the caution code of the 75 code rate. Whenever no code is received both of these relays 2H and 2D are deenergized. This decoding apparatus may be of

any suitable type such as shown for example in the Patent No. 2,342,489 granted N. D. Preston February 22, 1944, or such as shown in Fig. 2 of the accompanying drawings, but only the dotted rectangle has been indicated for the sake of simplicity in the disclosure of this Fig. 1.

It will of course be understood, that suitable driven code transmitting and inverse code receiving apparatus is associated with the leaving end of track section 1T, but this has been merely indicated by a suitable dotted rectangle in which the relay 2CP is shown and from which the inverse decoding relay 2AH is indicated as controlled. This apparatus is of course the same as that shown at the leaving end of track section 2T. Normally inverse code pulses are being received so that the relay 2AH is picked up, but assuming that a train is approaching on the track section 1T, this relay 2AH would be dropped away closing its back contact 23. Assuming that a clear code is being received by the track relay 2TR and the associated decoding apparatus, circuits would be closed from (+) through back contact 23, front contact 24 of relay 2H, front contact 25 of relay 2D, the green lamp G of signal 2, to (-), thus causing signal 2 to give a clear indication. If, however, a caution code were being received by the decoding apparatus, the distant relay 2D would be dropped away while the relay 2H would be picked up so that the yellow or caution lamp Y of signal 2 would be energized through back contact 25. On the other hand, if a train were standing in the track section 2T, so that no code is being received by the coding apparatus at signal 2, both the relays 1D and 2H are dropped away and the red lamp R of signal 2 is energized through back contact 24 of relay 2H, thus causing this signal 2 to indicate danger or stop.

Upon each deenergization of the track relay 2TR during the reception of a driven code, a circuit is closed through back contact 26 for energizing the repeater relay 2TPB by an obvious circuit. During its pick up period, which may be suitably adjusted by well-known means and design of such a relay, a circuit is closed for the inverse code transmitting relay 2TPA from (+), through back contact 26 of relay 2TR, back contact 27 of relay 2TPB, winding of relay 2TPA, to (-). As soon as the relay 2TPB picks up and opens back contact 27, the relay 2TPA is deenergized. The relative pick up and drop away times of these relays is so selected and organized that the relay 2TPA is picked up for a short period during each deenergization of the track section 2T between successive driven code pulses.

The closure of the advanced contact 21 of relay 2TPA connects the output terminals of the rectifier unit 2RA through a limiting resistor 37 to the track rails of section 2T. Since the transformer 2TFA is supplied with alternating current from a suitable source indicated by (BX) and (CX) its secondary winding applies a voltage through the winding 31 of the auto-reactor 2RTA to the input of the rectifier unit 2RA. Thus, the output of the rectifier 2RA supplies a potential to the track rails, but the current flow in this circuit is relatively small since the impedance of the resonated auto-reactor 2RTA is relatively high. However, as soon as the retarded contact 28 of relay 2TPA closes, the outer terminals of the auto-reactor 2RTA are shunted, which reduces the reactance to substantially zero, so that substantially the full voltage of the secondary winding of the transformer 2TFA is applied to the input of the rectifier unit 2RA. Thus, an inverse code pulse

is applied to the track section 2T of a value as determined by resistor 31 and the conditions of the track circuit, which inverse code pulse is received by the inverse code track relay 3ATR, as previously described. The auto-reactor 2RTA is constructed and is controlled by the retarded contact 28 of relay 2TPA in exactly the same way as described for the auto-reactor 3RT used to control the driven code pulses. In other words, the advanced contact 21 of relay 2TPA may be constructed of suitable low resistance material, such as silver, since only a relatively low potential and current is controlled by this contact, while the retarded contact 28 may be constructed of suitable high resistance contact material, such as tungsten, for reasons previously explained. The current controlled by the contact 28 is relatively low in view of the winding ratio of the auto-reactor 2RTA, and the associated resonating condenser 29 acts to absorb any arc at the contact 28 when it is broken at the end of the inverse code impulse period. It can be seen from the above that each inverse code pulse period is of a duration equal to the pick up period of the relay 2TPB together with the drop away period of the relay 2TPA, and these values are so chosen, as above mentioned, that the inverse code pulse will cease in plenty of time before the driven code pulse is applied at the opposite end of the track section.

Although for the purposes of this particular embodiment of the present invention, auto-reactors, such as 3RT and 2RTA are used for controlling the driven code pulses, and for controlling the application of the inverse code pulses, it should be understood that a usual transformer with separate primary and secondary windings could be just as well employed and still accomplish the functions of the present invention. Such an organization is shown in Fig. 1B, where the primary winding of such a transformer 3RT¹ is connected in the input of the rectifier 3R the same as winding 6 of Fig. 1; while its secondary has the condenser 9 connected across its outer terminals, and such outer terminals are shunted and unshunted by the contact 8 of the transmitter relay 3CP. Since the characteristics of the secondary load are transferred to the primary of a transformer, the condenser 9 connected across the secondary has such a value as to resonate the transformer and also to act to absorb or suppress any arcing from the associated controlling contact. The operation of such a modification is exactly the same as that already described. Although the auto-reactor has been disclosed as a preferred form, it is to be understood that any embodiment of the invention using a transformer having separate primary and secondary windings is intended to be within the scope of the present invention.

As above mentioned, the inverse code receiving track relays, such as 3ATR for example, are preferably made slow acting in being actuated to their lower or dropped away positions. In Fig. 1 this is accomplished by the provision of a front contact shunting the upper winding of the relay. But it is to be understood that this may be accomplished in different ways such as shown for example in Fig. 1A, where a rectifier unit 30 is shown as shunting the upper winding of relay 3ATR¹. This rectifier 30 is included in the shunting circuit for this upper winding in such a direction that the inductive impedance of this upper winding is effective when the lower winding is energized in a direction to actuate the contacts to their lower positions, but is not effective (due

to its high resistance to current flow in a backward direction) when the intermediate winding of the relay is energized by an inverse code pulse. The complete circuits have not been shown in Fig. 1A, since it is to be understood that this relay 3ATR¹ may be directly inserted in Fig. 1 in place of the relay 3ATR.

Fig. 2 form of the invention.—With reference to the accompanying Fig. 2 of the drawings, a stretch of track has been divided into track sections by suitable insulated joints of which the track section 5T has been shown completely and track sections 4T and 6T in part only. Color light type signals 5 and 6 are shown at the entrance ends of track sections 5T and 6T respectively. These signals can of course be of any suitable desired type.

At the exit end of each track section is suitable driven code transmitting apparatus governed by the code receiving apparatus for the entrance end of the next adjacent track section in advance, so as to apply different driven codes in accordance with traffic conditions in advance. At the entering end of each track section is a suitable code receiving organization indicated in the drawings as including a track relay 5TR of the polarized biased type, this is, this relay 5TR responds to only a particular polarity to be actuated to an operating position, and is biased to a normal position.

Each code following track relay, such as relay 5TR, governs suitable decoding apparatus of any well-known construction, such as shown for example in the Patent No. 2,342,489 granted to N. D. Preston February 22, 1944, and such decoding apparatus has been diagrammatically illustrated as including a decoding transformer 40 which has a mid-tapped primary winding controlled by contact 41 of the track relay 5TR so that this transformer is energized in opposite directions alternately as the contact 41 of the track relay 5TR is operated to its opposite positions in response to driven code pulses. The secondary winding of this decoding transformer 40 is mid-tapped and connected to the home relay 5H in combination with a rectifying contact 42 so that the relay 5H is picked up whenever the track relay 5TR is receiving driven code pulses of either the clear or caution code rates, but is dropped away whenever there is an absence of such code pulses. A suitable tuned decoding transformer 38 has its primary connected to another secondary winding of the transformer 40, while its secondary is connected through the rectifier unit 43 to the distance relay 5D. This circuit is tuned by the condenser 39 so as to pick up the relay 5D only when the track relay 5TR is operating at the clear code rate which for the purposes of this disclosure is to be 180 pulses per minute.

These home and distant relays 5H and 5D govern the indications of the associated signal 5, as will be readily understood from the drawings, while the home relay 5H also acts to select between the particular coding contacts which are to govern the driven code rate for the transmitting relay for the section next in the rear (not shown). Such coding contacts 180C and 75C have been shown as associated with the signal 6, and these contacts are assumed to be operating 180 times per minute and 75 times per minute respectively to provide the usual code rates, but it will be readily appreciated that various other rates may be selected if desired. These coding contacts 180C and 75C may be of any

suitable type, that is, they may be motor driven, or they may be code oscillators of the type disclosed in the patent to O. S. Field No. 2,351,583 dated June 20, 1944.

At the exit end of each track section, such as shown for the track section 5T, a transformer 6TFA has its primary winding energized from the opposite terminals (BX) and (CX) of a suitable alternating current supply; while its secondary winding is connected in series with the secondary winding of a like transformer 6TFB across the opposite terminals of the input of a full-wave rectifier 6R. The output of the rectifier 6R is connected through the limiting resistor 44 to the rails of the track section 5T.

The primary winding of the transformer 6TFB is supplied with alternating current from the same source as transformer 6TFA when the back contact 45 of relay 6CP is closed. Since the primary-secondary winding ratios of the transformers 6TFA and 6TFB are substantially identical, and since the windings of the transformers are so connected that the output potentials of their secondaries are in opposition, there is no potential applied to the rectifier 6R under such condition. On the other hand, when the contact 45 of the relay 6CP is picked up, the alternating current energy is removed from the primary winding of the transformer 6TFB, and such primary winding is also shunted through front contact 45. This not only removes the opposing potential of the secondary winding from the series circuit across the rectifier, but also substantially removes the inductive reactance of such transformer so that a potential, as supplied by the secondary winding of the transformer 6TFA, is applied to the opposite terminals of the rectifier 6R. The output of the rectifier 6R is fed to the rails of the track section to energize relay 5TR at the entering end. It is noted here that the track relay 5TR at the entering end is connected across the track rails through limiting resistor 46 and back contact 47 of relay 5TPC.

The condenser 48 and a series resistor 49 are connected across the opposite terminals of the secondary of transformer 6TFB and in multiple with front contact 45 of relay 6CP so as to act as an arc suppressing unit for the front contact 45. It should be noted that condenser 48 does not resonate transformer 6TFB, nor does it materially affect the phase of the output of the secondary of transformer 6TFB because of the low capacity of such condenser.

The code transmitting relay 6CP is controlled through front and back points 50 of relay 6H so as to be operated at the selected code rate, and while front contact 45 of relay 6CP is closed, code pulse energy is supplied to the track section 5T, but when back contact 45 is closed, the opposing potential of the secondary of transformer 6TFB prevents the flow of current to the track rails of section 5T. In this way, code pulses are applied to the rails of the track section 5T at the particular selected code rate.

Each track section has associated therewith an inverse code receiving relay 6ATR at the leaving end and suitable inverse code transmitting apparatus at the entering end of the track section including a rectifier 5RA, a transformer 5TFA and a transformer 5TFB, as well as a transmitting relay 5TPC controlled through repeater relays 5TPA and 5TPB as will presently be described.

Since it is desired to first point out the operation of the driven code transmitting apparatus,

it will be assumed for the present that only a driven code is being transmitted through the track section. It will be apparent that the current supplied through back contact 45 to the transformer 6TFB is merely of a sufficient amount to supply the power losses of such transformer, and that the closure of front contact 45 causes a current flow through it, although the actual current of the driven code pulse is supplied by transformer 6TFA. The front contact 45 and circuit shunting the primary of transformer 6TFB will carry a current having a value dependent upon the potential drop across the secondary of the transformer 6TFB and dependent upon the ratio of turns between the primary and secondary windings. Since this is a short circuit condition for the transformer 6TFB, the potential across the secondary winding of this transformer will be fairly low because of the impedance of the track circuit load, so that the current through front contact 45 is not excessive. But since there will be some magnetic flux change in the transformer due to the opening of front contact 45 at the end of the impulse period, it is desirable to employ the condenser 48 and the series resistor 49 connected in multiple therewith to absorb any sudden changes in current conditions produced by the opening of front contact 45. In other words, although the arrangement of the transformers provides for a minimum of arcing at the contact 45, it is desirable to further reduce this arcing by the use of condenser 48. The series resistor 49 is included so that should the condenser 48 be substantially charged during the change-over of the contact 45 from a back point to a front point, the discharged current of the condenser will be limited by the series resistor 49.

The voltage supplied to the primary winding 40 of the transformer 6TFB may be of any suitable value, such as a commercial 110 volt supply, but since this value is usually a relatively high potential, as compared to the track circuit potentials which may be in the order of 6 volts, for example, the contact 45 can be readily constructed of a relatively high resistance material, such as tungsten, and thus provide for long and reliable service. In other words, higher contact resistance materials may be used in such a circuit, since the potential is sufficient to break down any contact resistance and thus reliably supply the required current.

Assuming that each track section of a block signalling system is organized as above described, 55 and that a 180 clear code is being received over the track section 6T so that the home relay 6H is picked up, then the relay 6CP is being operated at the 180 code rate, and the signal 6 is of course indicating green or proceed. On the 60 other hand, if the relay 6H were deenergized due to the absence of code in the track section 6T, the relay 6CP would be operated at the 75 code rate and driven code pulses would be applied to the track section 5T in a manner above described. 65 These impulses would be received by the track relay 5TR causing the signal 5 to be controlled in accordance with such codes.

When a 180 code is received at the signal 5, the track relay 5TR operates contact 41 at the 180 70 code rate so that should a train approach this signal and cause the deenergization of the approach decoding relay 5AH and close back contact 51, then the signal 5 would indicate green by reason of a circuit from (+) closed through back contact 51 of relay 5AH, front contact 52

of relay 5H, front contact 53 of relay 5D, lamp of signal 5, to (-). But if a 75 code is being received, then the relay 5D will be dropped away and the yellow lamp Y will be energized through back contact 53. On the other hand, if there is no code being received at signal 5 due to the presence of a train in track section 5T, both relay 5D and 5H will be dropped away, so that the red lamp will be energized through back contact 52 of relay 5H.

The transmission and reception of inverse code pulses will now be considered. More specifically, upon the reception of each driven code pulse, the relay 5TR is picked up closing front contact 41 which causes current to flow through the upper half of the primary winding of the transformer 40. When this contact 41 assumes its lower or dropped away position upon the end of the driven code pulse, then the inductive reactance of the transformer 40 causes a surge of energy to charge the condenser 54 and in so doing causes a current flow through the upper winding of the relay 5TPC of sufficient value and in a direction proper to pick up its contacts. Since the relay 5TPC is of the magnetic stick type, its contacts remain in picked up positions after the surge of current through its upper windings has ceased.

At substantially the same time, the closure of back contact 41 causes current to flow through rectifier unit 55 and through the relays 5TPA and 5TPB in multiple, the circuit for relay 5TPB including back contact 58 of relay 5TPA. The relay 5TPB picks up after a short interval of time followed by the picking up of the relay 5TPA which opens the circuit for relay 5TPB at back contact 56. In other words, the relay 5TPA is slightly slower to pick up than the relay 5TPB, and this can be accomplished by adding a suitable resistor in multiple with the relay 5TPA.

After a short interval of time, the relay 5TPB releases, and this interval of time can be made of suitable value by adding a rectifier unit in multiple with its windings, and thus slightly delay its drop away. But when the relay 5TPB drops away, the relay 5TPA is still picked up, so that there is a circuit from (+), through front contact 57 of relay 5TPA, back contact 58 of relay 5TPB, front contact 59 of relay 5TPC, lower winding of relay 5TPC, to (-). The current which flows in this circuit is of such a direction as to cause the contacts of the magnetic stick type relay 5TPC to be actuated to their lower positions to open contact 59 and immediately break such circuit. This happens before the end of the "off" period between two successive driven code pulses. In order to suppress any arcing which may occur at contact 59, a suitable condenser 60 may be placed in multiple with the lower winding of relay 5TPC.

Thus, it can be seen that at the end of each driven code pulse, the relay 5TPC is actuated to a picked up position to apply an inverse code pulse to the track section 5T, and after a short period of time is restored to mark the end of the inverse code pulse.

More specifically, when the relay 5TPC is picked up it opens back contact 47 to disconnect the track relay 5TR, and closes front contact 47 to connect the output of the rectifier unit 5RA through the limiting resistor 62 across the rails of the track section 5T. The opening of back contact 63 of relay 5TPB disconnects the source of energy from the primary of the transformer 5TFB, and shunts such winding through

front contact 63 to remove the inductive reactance of this transformer from the input circuit of the rectifier 5RA so that it can receive the necessary energy from the secondary of transformer 5TFA. The back contact 63 of relay 5TPB is opened and its front contact is closed slightly after the front contact 47 of relay 5TPC is closed. On the other hand, the relay 5TPB must drop to close its back contact 58 before the relay 5TPC is actuated to its lower position, thus, the back contact 63 is closed applying a potential in opposition to the potential produced by the secondary winding of transformer 5TFA before the front contact 47 is opened and the back contact 47 closed. In this way, the contact 47 is used to commutate the track relay and inverse code energy applying circuit across the track rails at times at which there is no energy flow to the track rails. For this reason, there is no arcing at the front and back points of the contact 47, and these contacts may be of suitable low resistance contact material, such as silver for example. The energy controlling contact 63 may be constructed of suitable high resistance contact material, such as tungsten, since it controls the losses in the transformer 5TFB at a relatively high voltage, as described in connection with contact 45 of the relay 6CP.

The application of an inverse code pulse to the track section 5T occurs at a time when the driven code transmitting relay 6CP is dropped away, so that there is no potential across the input terminals of the rectifier 6R. The inverse code energy flows from the lower track rail through the rectifier unit 6R and the limiting resistor 44 to the upper track rail. This produces a potential drop across the rectifier and the limiting resistor 44 so that a current flow is produced in the lower winding of the relay 6ATR to the right and through back contact 64 of the transmitting relay 6CP to the upper terminal of resistor 44. This causes the contacts of the inverse code receiving track relay 6ATR to be picked up, and since this is a magnetic stick type relay, its contacts remain picked up although the inverse code pulse ceases. It should be noted in this connection, that the potential across the lower winding of relay 6ATR is during an inverse code pulse substantially the same as that across the track rails, except perhaps for the potential drop that is caused in the lead wires from the track. Although the rectifier unit 6R and limiting resistor 44 are shunted across the track rails of section 5T under such a condition, it should be recognized that such a shunt has a higher effective resistance than would at first be apparent, because the relatively low potential at this end of the track circuit finds that the forward resistance of the rectifier unit 6R is relatively high, which forward resistance is added to the particular adjustment of the limiting resistor 44. In other words, rectifier units, especially those of the copper oxide type and the like, have a relatively high forward resistance for low potential and current values. The rectifier units when employed for applying energy to the track circuit are dealing with higher potentials and the forward resistance is relatively low, but when used to receive energy over the track rails at very low potential, the resistance is higher accordingly, and this factor should be taken into consideration in considering the potential drop across the lower winding of the relay 6ATR upon the reception of inverse code pulses.

Upon the following driven code pulse, the relay 6CP is picked up closing front contact 64 so that the lower winding of relay 6ATR is connected through limiting resistor 65 to the output terminals of the rectifier unit 6R, causing current to flow in a left-hand direction through the lower winding of relay 6ATR actuating its contacts to their lower or dropped away positions. In this way, the relay 6ATR is picked up upon each inverse code pulse and is caused to be dropped away upon each driven code pulse by reason of a local circuit. The actuation of the contacts of relay 6ATR to their lower positions is caused to be retarded by reason of its upper winding being shunted by front contact 66. This is so that the contacts of the relay 6ATR will be in their upper and lower positions substantially the same length of time even if the inverse code pulses are of relatively short duration.

It will be readily apparent how a stretch of track having its several track sections equipped with coded track circuit apparatus as disclosed herein will provide for the control of the signals to give three indication signalling for the passage of traffic in an east bound direction, so that a detailed consideration of the passage of a train will not be given, and especially since it is believed that the above description clearly points out the condition of the signals during the presence and absence of a train and the different code rates.

Having described two forms of a coded track circuit block signalling system employing code transmitting apparatus organized to give a minimum amount of arcing at the code transmitting contacts as embodying the present invention, it is desired to be understood that the invention is shown in this connection for the purpose of facilitating its disclosure, and that it can be applied to systems of various other types. Although the invention has been shown embodied in two different forms, it is to be understood that other specific embodiments and modifications of the invention may be made, and that various adaptations and alterations may be required to meet the problems of practice without in any manner departing from the spirit or scope of the present invention except as limited by the appended claims.

What I claim is:

1. In a coded track circuit signalling system for a section of railway track, a code transmitter comprising, a source of alternating current, a rectifier unit, an inductive reactor unit including windings, circuit means connecting said alternating current source across the rails of said section through a portion of said reactor windings and rectifier units in series, and a coding contact intermittently acting to shunt said reactor windings to thereby permit the intermittent application of direct current code pulses to said section of track.

2. In a coded track circuit for railroads, a driven code transmitter comprising, a code transmitter relay having a contact intermittently operated to its opposite positions in accordance with different selected code rates, a full-wave rectifier unit having input and output terminals, circuit means effective to connect the output terminals of said rectifier across the rails of said track section, a reactor unit of the auto-transformer type having a condenser connected across its outer terminals to effect its resonance at a particular frequency, and having a mid tap connected to one input terminal of said rectifier, a source of

alternating current connected to the other input terminal of said rectifier and one outer terminal of said auto-transformer, and circuit means including said contact of said transmitter relay

5 for intermittently shunting the outer terminals of said auto-transformer, whereby a succession of driven code impulses are applied to said track rails which impulses are controlled by said contact of said transmitter relay at a potential substantially higher than the actual potential applied to said track rails.

3. In a code transmitting organization having driven code pulses transmitted at different code rates, a code transmitting relay intermittently 15 operated to its opposite positions in accordance with different selected code rates and having advanced and retarded contacts both being closed in the same position, but said advanced contact being closed slightly prior to the closure of said 20 retarded contact and being opened slightly subsequent to the opening of said retarded contact, a full-wave rectifier having input and output terminals, circuit means including said advanced contact for intermittently connecting said rectifier output terminals to a track circuit, a reactor unit, a source of alternating current connected to the input terminals of said rectifier through a portion of said reactor unit, and circuit means including said retarded contact for shunting said 25 reactor unit during each period when said rectifier output terminals are connected to the track circuit.

4. In a coded track circuit for railroads operable to transmit off-code current pulses in one 30 direction during off intervals between driven code pulses transmitted in the opposite direction, code transmitting and receiving apparatus at the driven code transmitting end of the track section comprising, an off-code track relay responsive 35 to off-code pulses, a full-wave rectifier having input and output terminals, a transmitter relay intermittently energized and deenergized in accordance with different driven code rates and including advanced and retarded contact means, 40 circuit means including said advanced contact means operated by said transmitter relay for alternately connecting and disconnecting said off-code track relay and the output terminals of said rectifier across the rails of said track circuit, and 45 circuit means including an alternating current source and said retarded contact means on said transmitter relay for applying energy to the input terminals of said rectifier subsequent to each of its connections to said track rails, said circuit means being effective to remove energy from the input of said rectifier prior to each of its disconnections from the track rails, whereby said advanced contact means is not required to make or break the load current supplied to said track 50 rails during each driven pulse application.
